UNITED STATES PATENT OFFICE.

AUGUST HILDT, OF NEW YORK, N. Y., ASSIGNOR TO LOUIS DRYFOOS & CO.,
OF SAME PLACE.

DESIGN FOR THE ORNAMENTATION OF SKIRTS, LININGS, &c.

SPECIFICATION forming part of Design No. 17,811, dated October 25, 1887.

Application filed September 5, 1887. Serial No. 248,908. Term of patent 7 years.

To all whom it may concern:

Be it known that I, AUGUST HILDT, a citizen of the United States, and a resident of the city, county, and State of New York, have invented a new and Original Design for Surface Ornamentation of Skirts, Linings, and other Similar Articles, of which the following is a specification.

My designs is for the surface ornamentation of skirts, linings, quiltings, and similar articles; and it consists of the parallel rows of separated and tangent circles and the intervening lozenge-shaped figures or parallelograms arranged and disposed all as will hereinafter more fully appear.

In the accompanying drawing I have represented in a single figure a portion (containing all the elements) of my design as it appears when applied to or upon the article or goods, dotted lines being employed to indicate stitches, and these lines arranged or grouped in accordance with my design, this illustration being deemed sufficient for purposes of this specification.

For convenience of description the various parts of the design may be referred to as follows: A A A are circles located one above the other or in parallel rows, of any number, and distant from each other, as will be observed, about the length of one diameter. B B B are circles similar to the circles A A A, and are similarly disposed and spaced, forming a row or line of circles parallel with the first. The two rows are separated from each other by a distance near or about three diameters of one of the circles, in order that the intervening lozenge-shaped figure may be suitably proportioned. Any number of these vertical rows of circles may be added, and thus the design made to cover any desired extent of surface.

Between the circles A A and B B are straight lines of stitching extending from the extremity of the horizontal diameter of one circle to corresponding points on circles in the next row, and the arrangement is such as to form a series of lozenges or parallelograms, as a b c d, touching at their angles and lying between the vertical rows of circles. These lozenges will be varied in size by varying the size of 50 and distance between the circles.

The description so far indicates the general principles upon which the lines and circles are grouped.

To increase the number of lines and circles in any given space, the same general arrangement is followed for the groundwork, and upon this or to this is added another series of lines and circles precisely like the first, as indicated at the lower part of the figure, wherein, for instance, a circle, as A', has its center 55 located midway between the adjacent circles A A. The same arrangement is followed in each vertical row, affording (in the part wherein the lines are increased) rows of circles tangent to or touching each other. 65

The cross-lines between all the rows drawn, as before explained, form a series of small lozenges, as will be readily seen, and these fill the space between the vertical rows of circles.

The groundwork alone may constitute the 7c whole design in any pattern, or the duplicate thereof may be employed entirely. I prefer to employ both together, the lower part forming a heavy margin for the pattern, while the upper part appears lighter; but the upper and 75 lower parts might be reversed, if desired.

The design is to be distinguished from one in which the groundwork or base includes rows of circles tangent to each other, and also from one in which the lower or heavier part 80 shows circles intersecting each other and not tangent one to the other, as herein illustrated.

I do not broadly claim herein a design made up of vertical rows of circles and intervening lozenge figures; but,

Having now fully described my design, what I do claim as new, and desire to secure by Letters Patent, is--

The herein-described design for the ornamentation of skirts, &c., consisting of the parallel 90 rows of separated and tangent circles and the intervening lozenge-shaped figures or parallelograms, under the arrangement substantially as shown and described.

In testimony whereof I have hereunto set 95 my hand.

AUGUST HILDT.
